UNITED STATES PATENT OFFICE

2,582,591

LATCH FOR SLIDABLE SIDE JAW
WRENCHESMaxwell K. Hicks and Arthur G. Hicks,
Denver, Colo.

Application June 26, 1950, Serial No. 170,398

1 Claim. (Cl. 81—145)

1

This invention relates in general to wrenches and in particular to an adjustable wrench with one fixed jaw and one sliding jaw with rack and rack engaging lock.

In the design of adjustable wrenches, with which the prior art is replete, several important factors are involved. First; is ease and rapidity of adjustment and release. Second; is simplicity of construction with a minimum number of parts and, third; is strength and a high factor of safety.

When setting a wrench to a bolt head or nut it is desirable to eliminate the old time-consuming process of repeated setting and trying the wrench until its adjustment is correct.

Oftentimes, a mechanic who is a bit careless or who is pressed for time will not take the necessary precaution to properly adjust the wrench, and when force is applied while turning a nut the wrench will slip, resulting in injury to the mechanic and damage to the nut.

In other wrenches, once set to the nut, adjustment may be accidentally altered when the wrench is laid down and moved around, and when the mechanic starts to use it again he must readjust it.

With our wrench the setting is quickly and easily made and once set the wrench will remain in adjusted position regardless of how the wrench is handled until a new setting is desired.

The objects of our invention are, first; to provide an adjustable wrench with one fixed jaw and one movable jaw, a rack on the movable jaw, a rack catch or lock normally urged into engagement with the rack to hold the movable jaw against movement, and means for temporarily moving the rack lock out of engagement with the rack to permit sliding movement of the movable jaw for adjustment thereof in relation to the fixed jaw.

Second; to provide a wrench of the class described which can be easily and quickly adjusted to the nut which is to be turned and which can be quickly released therefrom.

Third; to provide a wrench of the class described which can be adjusted in small increments.

Fourth; to provide a wrench which when adjusted will not have any play to affect the adjustment.

Fifth; to provide a wrench with one fixed and one sliding jaw, and a sliding jaw engaging member movable transversely into and out of jaw engaging position.

Other objects and advantages as well as the construction and operation of our invention will

be apparent by reference to the following specification in connection with the accompanying drawing in which:

Fig. 1 is a front elevational view of the wrench comprising our invention, with the jaws in open position.

Fig. 2 is a top plan view of the same.

Fig. 3 is a view similar to Fig. 1 with parts broken away in section on line 3—3 of Fig. 2, to better illustrate certain other parts.

Fig. 4 is a fragmentary view of the wrench with parts in section showing the jaws abutting each other and the jaw engaging member in released position.

Fig. 5 is a fragmentary sectional view on the line 5—5 of Fig. 4.

Referring now to the drawing by numerals of reference, 1 designates the wrench handle or body with enlarged head 2 and fixed jaw 3 extending therefrom.

The head 2 is provided with a slotted guide 4 in transverse relation to the fixed jaw 3. A reduced slot 5 cooperates with slotted guide 4 in a manner hereinafter disclosed. A recessed chamber 6 receives locking mechanism which will be described later in this specification.

A sliding jaw 7 has reduced guide portion or web 8 slidable in the reduced slot 5 and a transverse rack 9 mountable for sliding movement in the transverse slotted guide 4. A stop pin 10 prevents removal of the sliding jaw 7 and limits its maximum opening. The rack as shown is substantially the same length as the slotted guide 4 in which it is positioned. The jaws 3 and 7 will always remain in parallel relation.

A rack catch or lock 11 is positioned in chamber 6 and is normally urged into engagement with rack 9 by spring 12 held in place at one end in the body of the wrench. The bottom edge 11' of rack lock 11 rides on surface 6' of chamber 6.

The upper end of the rack lock 11 abuts flattened pin 13 against which the rack lock slides as it is moved into and out of rack locking position.

A rack lock lever 14 is pivoted at 15 in chamber 6 and is provided with circular end 16 which engages slightly larger circular opening 17 in the rack lock 11. Pressure on the rack lock lever 14 will cause rectilinear movement of the rack lock to release the rack lock from the rack 9 permitting free sliding movement of the rack and slidable jaw 7. Release of finger pressure on the rack lock lever will permit the spring 12 to urge the rack lock into engagement with the rack. This essentially is the operation of our wrench.

With the rack released by finger pressure on the rack lock lever, the wrench is placed on a nut with the fixed jaw bearing against the nut. The slideable jaw is then forced against the other side of the nut and the rack lock lever released. The wrench can be taken off the nut without affecting the adjustment. When laid down the adjustment of the wrench will not change as is true with other adjustable wrenches which may be moved around on a bench top or the like.

If it is desired to move the slideable jaw to fully extended position it is merely necessary to hold the wrench with the rack in substantially vertical position and the slideable jaw downward, and then push the rack lock lever 14, the rack and jaw gravitating to full open position.

The teeth on the rack and rack lock can be made as small as practical consistent with good engineering and machining practice so that fine increments of wrench adjustment can be obtained.

The rack lock 14 will engage a substantial portion of the rack, and the stresses, when the wrench is under pressure, will be well distributed, although very little force is transmitted through the teeth of the rack or rack lock except what passes therethrough and is exerted on the surface 6' of the chamber 6.

When under pressure in turning a nut, the shoulder 18 of sliding jaw 7 will bear against the face 19 of the enlarged head 2 and also the offset edges 20 of the rack will bear against edges 21 of the transverse slotted guide 4. The large amount of bearing surface will provide a much greater factor of safety than is necessary in such a tool.

From the foregoing it will be seen that we have provided a relatively simple and efficient adjustable wrench which can be quickly and easily adjusted to fit the nut on which it is to be used, and which will not have its adjustment accidentally changed when the wrench is not being used.

It is obvious that changes in form, proportion and details of construction may be resorted to without departing from the spirit of our invention and we reserve all rights to such changes as come within the scope of these specifications and the claim which follows.

What we claim as new and desire to secure by Letters Patent is:

In an adjustable wrench, an enlarged head, a

fixed jaw extending from the head, a slotted guide in the head, oppositely disposed reduced slots on two sides of the slotted guide, a rack slidably carried in the slotted guide, a reduced toothed web on one side of the rack and positioned in one of the reduced slots, a second reduced web carried by the opposite side of the rack and positioned in the other reduced slot, a jaw carried by the last mentioned web, an exterior bearing surface on the enlarged head, a bearing surface on the jaw adapted to ride the exterior bearing surface on the enlarged head, the rack bearing against the slotted guide at the reduced slots therein, a reduced slot extension in the enlarged head, a flat surface in the reduced slot extension transverse to the slotted guide in the head, a pin spaced from the flat surface and having a flat portion parallel to said flat surface, a rack lock positioned in the enlarged head and slideable between the flat surface in the reduced slot and the flat portion on the pin, a rack lock lever operatively connected to the rack lock and having a portion thereof extending from the enlarged head, a spring normally urging the rack lock into engagement with the rack to lock the second mentioned jaw in immovable adjusted relation to the fixed jaw, pressure on the rack lock lever releasing the rack lock from the rack and permitting free slideable movement of the rack and the jaw carried thereby.
